DANCING FOOTWEAR AND TAPS FOR
DANCING FOOTWEAR

Charles H. Buckler, Camden, N. J.

Application April 10, 1937, Serial No. 136,206

2 Claims. (Cl. 36—8.3)

This invention relates to footwear for dancing and the like, and more particularly to footwear for tap dancing and to taps for tap dancing footwear.

The principal object of the invention is to provide an aid in dancing and the like, which will make it possible for the dancer to glide or spin with a minimum of effort and without the friction or retarding of steps characteristic of conventional dancing footwear and footwear equipped with conventional taps.

Another object is to provide an anti-friction dancing tap which may be inserted into the bottom portions of conventional footwear or into conventional tap soles or plates.

Still another object is to provide an aid in tap dancing which may be readily removed or replaced and wherein the aid may be replaced in toe tap plates without removing the plates themselves from the footwear with which they are associated.

Other objects and advantages of the invention will be apparent during the course of the following detailed description, taken in connection with the accompanying drawing, forming a part of this specification and in which drawing:—

Figure 1 is a bottom plan view of an article of footwear containing the novel taps.

Figure 2 is a side elevation of the same, with parts broken away to better illustrate portions of the construction.

Figure 3 is a vertical section of a novel tap.

Figure 4 is a top plan view of the same.

Figure 5 is a conventional footwear heel, before the novel taps, shown in Figures 3 and 4, are attached thereto.

Figure 6 is a conventional tap sole or plate before the taps, shown in Figures 3 and 4, are attached thereto to become a part thereof.

In the drawing, wherein for the purpose of illustration is shown a preferred embodiment of the invention, and wherein similar reference characters designate corresponding parts throughout the several views, the letter A may embrace and designate footwear B equipped with the novel taps C and an assembly of the novel taps C and a tap sole or plate D.

The footwear B, shown by way of example, is a conventional dancing shoe or pump, including a sole portion 10 and a heel portion 11, both of substantial thickness.

If it is desired to provide the novel footwear with heel taps, the heel portion 11 may be provided with one or a suitable number of sockets

or openings 13, extending upwardly from its lowermost face 12.

Each of the novel taps C, preferably includes a cylindrical body or plug portion 14 having a concaved socket or recess 15 extending from its lower face 16, as shown in Figure 3. This socket 15 accommodates a suitable rollable or rotatable member, preferably a sphere 17, with a portion of the sphere protruding outwardly of the socket and beyond the lower face 16. Extending outwardly at the lower end and beyond the periphery of the cylindrical body portion 14 is a flange 18, the uppermost face 19 of which constitutes an abutment to prevent inward movement of the taps when in place.

Means is provided to retain the sphere 17 within the recess 15 so that, while the former cannot drop out of the recess 15, it may roll therein. This means preferably comprises a disc 20 having a central perforation 21 so that the disc will encircle a portion of the sphere 17 at the portion thereof that extends outwardly of the body portion 14. The disc 20 has an upturned flange 22 which snugly engages the flange 18, as shown in Figure 3.

If desired, the body portion 14 may have a small perforation 23 extending from its upper end to the recess 15, as shown in Figure 3.

The assembly of one or more of the taps C with a tap sole or plate D is desirable, to provide a rolling tap for the toe end of the sole portion 10. The tap sole D may comprise a metallic plate 25 shaped to conform to the toe end of the sole portion 10. This plate 25 is provided with one or more openings 26 extending from its lowermost face 27 and, if more than one perforation or opening 26 is provided, spaced apart as desired. For example, a desirable arrangement of openings is that shown in Figure 6.

In addition, the plate 25 may be provided with nail or rivet head accommodating sockets 28, each having a perforation for the shank of the nail or rivet.

Nails, rivets or the like may constitute means 29 for securing the novel toe plate assembly to the sole, as is well known in the art.

Each perforation or opening 26 accommodates the body portion 14 of a tap C in a snug-fitting engagement, with the flange 18 in contact with the under face 27 of the plate 25. The novel taps C may be attached to the heel portion 11 by inserting the body portion 14 of each into a socket 13 and driving it in, in any approved way until the face 19 of the flange 18 abuts the lower face 12 of the heel portion 11. It has been found that

these taps C will not drop out of the several sockets and openings provided, but rather, the tapping to which they are subjected while in use tends to more firmly hold them in place. However, they 5 may be pried from the openings or sockets, when desired.

A method similar to that just described, or another method, may be employed to drive the body portions 14 of the taps C into the openings 26 in, 10 the plate 25 until the faces 19 of the flanges 18 abut the face 27 of the plate 25.

It is apparent that, by removing the disc 20 with its flange 22, a sphere may be substituted for a cracked or worn one.

15 The taps C, which are preferably wholly metallic, and their assembly with the plate D, constitute means to aid the wearer of the footwear to which they are attached in dancing, since the wearer may glide and spin with a minimum of effort and without the friction or retarding of 20 steps characteristic of conventional taps. There is, also, much less wear upon the novel taps than upon conventional taps, which must be replaced relatively frequently.

25 Various changes may be made to the form of invention herein shown and described, without departing from the spirit of the invention or the scope of the claims.

What is claimed is:

30 1. A dancing tap comprising a substantially cylindrical plug portion including an upper face

and a lower face and provided with a concaved recess extending inwardly from said lower face, said plug portion having a flange extending from the periphery thereof at the lower end thereof, a sphere carried partly within said recess and with a portion thereof extending outwardly beyond said lower face, and means to retain said sphere within said recess comprising a disc having a central opening with said opening less in diameter than the diameter of said sphere and encircling a portion of said sphere, and the thickness of said disc being less than the distance said sphere extends from said recess, said disc having an upwardly extending peripheral annular portion in tight-fitting engagement with the outer 15 peripheral face of said flange, said sphere constituting the tapping surface of said tap.

2. A dancing shoe having a tread portion of substantial thickness provided with a cylindrical recess extending upwardly from the lowermost 20 face of said tread portion and means including a cylindrical body extending into said recess in a tight-fitting relationship with said tread portion, said cylindrical body being of a length less than that of said recess, and having below its 25 lower face an annular portion extending outwardly beyond the body, and a freely rollable member carried by said means with a section of said rollable member extending below said means.

CHARLES H. BUCKLER.
